CLAIM

The ornamental design for a telephone set, as shown and described.

DESCRIPTION

FIG. 1 is a front and top perspective view of a telephone set showing my new design with the receiver in normal cradled position;

FIG. 2 is a front perspective view of the telephone stand with the handset inverted and set upon the stand;

FIGS. 3 and 6 are respectively right and left side elevational views of the telephone set in normal cradled position;

FIGS. 4 and 7 are respectively top and bottom plan views of the set in normal cradled position; and

FIGS. 5 and 8 are respectively front and rear elevational views thereof.
